Patented Feb. 15, 1916.

Inventor
James F. Beehler

UNITED STATES PATENT OFFICE.

JAMES F. BEEHLER, OF ST. LOUIS, MISSOURI.

BOX-FASTENER.

1,172,003.

Specification of Letters Patent.

Patented Feb. 15, 1916.

Application filed April 5, 1915. Serial No. 19,126.

To all whom it may concern:

Be it known that I, JAMES F. BEEHLER, a citizen of the United States, residing at St. Louis, Missouri, have invented a certain new and useful Improvement in Box-Fasteners, of which the following is a full, clear, and exact description, such as will enable others skilled in the art to which it appertains to make and use the same, reference being had 10 to the accompanying drawings, forming a part of this specification.

My invention relates to new and useful improvements in box fasteners, the principal objects of my invention being to provide a comparatively simple and inexpensive fastener or latching device for the lids of boxes, such as beer shipping cases, egg crates, and the like, and to provide a device which can be cheaply manufactured and 20 easily applied for use, and which device comprises a minimum number of parts.

Further objects of my invention are to generally improve upon and simplify the existing types of box fasteners, and to provide a device wherein the latching plate is provided with a latch receiving member, a sealing wire loop, a sealing wire guide, and a lifting lip.

With the foregoing and other objects in view, my invention consists in certain novel features of construction and arrangement of parts, hereinafter more fully described, claimed and shown in the accompanying drawings, in which—

35 Figure 1 is a top plan view of a portion of a box and showing my improved fastener applied thereto. Fig. 2 is a vertical section taken approximately on the line 2—2 of Fig. 1. Fig. 3 is an elevational view of the resilient latching member. Fig. 4 is a 40 sectional view similar to Fig. 2, and showing the latching member combined with a latching plate, which latter is applied to the inside of the box lid.

45 Referring by numerals to the accompanying drawings, 10 designates the front wall of a box, and 11 the lid or cover therefor, and formed in said cover near the front edge is a circular opening 12. Positioned immediately over this aperture 12 and secured to the box lid in any suitable manner is the latching plate of my improved device, the same being preferably constructed of a rectangular section 13 of sheet metal in the center of which is formed an aperture 14. This aperture is formed by pressing or

stamping out a section of the sheet metal of which the plate is formed and said stamped-out section is bent downwardly and thence forwardly so as to form an inclined striking plate 15 against which the upper end 60 of the spring latching member is adapted to engage when the lid is swung downward into closed position.

Formed in the plate 13 immediately in front of the opening 14 is a curved slit 16 and the material of the plate between this slit and the opening 14 is bent downwardly to form a horizontally disposed seat 17 which is engaged by the upper end of the 70 resilient latching member hereinafter more fully described. The front edge of this depressed seat engages directly against the edge of the box lid at the front of the opening 12, and thus serves as a guide for correctly positioning the plate 13 on the lid when said plate is applied thereto.

The material in the plate 13 between the slit 16 and the corresponding front edge of said plate is bent upward to form a loop 18 80 beneath which a sealing wire may be positioned. The material immediately to the rear of opening 14 is bent downward to form a depending lip 19, which latter bears directly against the rear edge of the opening 85 12 in the box lid and the inclined or rounded face of this downwardly bent lip serves as a guide to deflect the sealing wire upward when said wire is applied to the fastener. The material in the plate 13 adjacent to the 90 rear edge is bent upward to form a lip 20 which performs the functions of a lifting lip inasmuch as it may be engaged by the fingers when it is desired to lift the lid to which the plate is attached.

95 Fixed to the inner face of the front wall 10 of the box is a plate 21, the upper edge of which is bent outward to form a horizontally disposed plate 22 in the center of which is formed an opening 23.

100 Formed in the lower portion of plate 21 is a transversely disposed rib 24 in the top of which is formed an opening 25 and secured to the inside of said rib 24 in any suitable manner is the lower end of a vertically disposed resilient latching member 26, the same passing through openings 25 and 23. The opening 25 has greater width than the thickness of member 26, and thus any small particles of foreign matter which 110 may tend to accumulate between the plate 21 and the lower portion of member 26 will

pass downward through said opening into the space within rib 24, and consequently the free operation of the resilient member is not affected.

5 Formed in the central portion of member 26 is a short vertically disposed rib 27 which serves to stiffen the central portion of said member and prevent the upper portion thereof from being accidentally bent 10 outward and downward to an abnormal degree, thereby rendering said member inoperative. The upper portion of member 26 is bent forwardly to form a hook 28 which is adapted to engage directly over seat 17 15 when the latch is closed and the extreme upper end of said resilient member above the horizontal portion 28 is curved upwardly and rearwardly as designated by 29 to form a striking plate which engages the underside of striking plate 15 when the lid is closed.

Formed through the lower portion of the curved plate 29 is an aperture 30 which is adapted to receive a sealing wire. When the 25 sealing wire is applied, one end thereof is passed beneath loop 18 and thence through aperture 30 and as the end of said wire is moved forward it will strike against lip 29 and be deflected upwardly thereby, and the 30 ends of the wire are now brought together and united by a suitable seal.

When the lid of a box which is equipped with my improved fastening device is closed, the curved striking plate 29 strikes 35 against the underside of striking plate 15 and the upper end of the resilient member 26 moves rearward until the hook on the upper end of said member passes the upper edge of the striking plate 15 after which 40 said hook will spring forward into locking position immediately above member 17 and when so positioned the lid is maintained in closed position. When it is desired to release the fastener to permit the lid to be 45 raised, the upper end of the resilient member is forced rearwardly a short distance and the operator by now engaging lip 20 may raise said lid.

In Fig. 4 I have shown an inside keeper 50 or latching member associated with the member 26, said keeper comprising a plate 31 which is secured to the underside of the lid and said plate being provided with a de-

pendent portion 32, the lower end of which is bent upward to form a hook 33 which 55 when the device is closed engages beneath the horizontally disposed hook portion 28.

A box fastener of my improved construction is comparatively simple, can be cheaply manufactured, comprises a minimum number of parts, and is applicable for use on all forms of boxes, cases and crates utilized for storage and shipping purposes.

It will be readily understood that minor changes in the size, form and construction 65 of the various parts of my improved device can be made and substituted for those herein shown and described, without departing from the spirit of my invention, the scope of which is set forth in the appended claims. 70

I claim:

1. In a box fastener, a plate provided with an opening, a portion of said plate in front of said opening being bent upward to form a sealing wire loop, the edge of said 75 plate to the rear of said opening being bent downward to form a sealing wire guide, the rear edge of said plate being bent upward to form a lifting lip, and a resilient latching member, the upper end of which is provided with a hook which is adapted to pass through the opening in the plate and engage over that portion of said plate between the opening and the sealing loop.

2. The combination with a box and box 85 lid, the latter being provided with an opening, of a plate positioned over said opening, which plate is provided with an aperture, an inclined striking plate depending from said plate in front of said aperture, a sealing wire loop on said plate in front of the aperture, a lifting lip on the rear edge of said plate, and a resilient member secured to the front wall of the box, the upper end of which resilient member is provided with 90 a hook which is adapted to pass through the opening in the plate and engage the top of said plate in front of the opening therein.

In testimony whereof I hereunto affix my signature in the presence of two witnesses, 100 this 3d day of April, 1915.

JAMES F. BEEHLER.

Witnesses:

M. P. SMITH,
J. ADOLPH BISHOP.
